TRUCK SIDE FRAME

Filed Nov. 3, 1924

UNITED STATES PATENT OFFICE

THOMAS H. SYMINGTON, OF BALTIMORE, MARYLAND, ASSIGNOR TO THE SYMINGTON COMPANY, OF NEW YORK, N. Y., A CORPORATION OF MARYLAND

TRUCK SIDE FRAME

Application filed November 3, 1924. Serial No. 747,638.

The invention relates to side frames for car trucks and more particularly to cast steel side frames having journal boxes integral with said side frames.

5 The principal object of the invention, generally considered, is to provide a simple, strong and reliable construction of the type outlined in which the truss members are so formed that the neutral axes of the truss members intersect substantially on the line of application of the major load.

Still another object of the invention is to provide, in a car truck of the character described, a truss formation in which the 15 section of the neutral axes of the truss members is so located as to reduce to a minimum the moment arm of the forces which are applied approximately at the top of the journal box.

20 A further object of the invention is to so form the truss portions of the cast steel side frame of the type described that the secondary stresses set up therein by the elastic deformation of the parts are counter-balanced by increasing the cross-sectional area, the cross-sectional area of the truss members increasing from the points of contraflexure to points adjacent the journal box and strut members.

A still further object of my construction is 30 to provide in a side frame of the class described means by which the longitudinal forces transmitted to the journal boxes due to end thrust or brake application will be transmitted to the truss member of the side frame by a strut arranged substantially parallel with the direction of application of said forces.

To these and other ends the invention comprises the various elements and combinations 35 of elements as hereinafter set forth.

In the drawings which I have chosen to illustrate the invention:

Figure 1 is a view partially in side elevation and partially in longitudinal vertical 45 section of a truck side frame;

Figure 2 is a top plan view of one of the end portions of the construction illustrated in Figure 1;

50 Figure 3 is a transverse vertical sectional view taken on line 3-3 of Figure 1, the di-

rection of view being indicated by the arrows adjacent the ends of said section line;

Figure 4 is a transverse vertical sectional view taken on line 4-4 of Figure 2, the direction of view being indicated by the arrows adjacent the ends of said section line; and

55 Figure 5 is a fragmentary sectional view looking downwardly, the section being taken on line 5-5 of Figure 1.

Throughout the specification and drawings 60 like parts are designated by like reference characters.

The truck side frame 1 is of cast metal, preferably cast steel, provided with a cambered compression member 2, a tension member 3, and a strut member or bolster guide columns 4-4, all of said parts being integrally connected. The strut 4 serves to form the window or bolster and bolster spring seat opening 5 of the side frame. The compression and tension or truss members 2 and 3 of the side frame are provided with flanges which extend from their lateral edges, the 70 said flanges being connected at certain portions so as to form the side walls 6 of the side frame, the flanges of the tension member changing from upstanding flanges outwardly of the guide columns to depending flanges between said guide columns. The 75

construction might be described by stating that the lateral edges of the compression and tension members or the webs thereof are connected by side walls 6, the said side walls being interrupted by openings 7-7. The corresponding openings in each side wall are 80 located between the adjacent strut 4 and the end of the side frame. The walls 8 of the openings 7 are arranged at an angle to, rather than parallel with, the portions of the compression and tension members and each 85 wall 8 is preferably reinforced by an outwardly marginal flange 9 which preferably surrounds the entire opening. The purpose and object of thus shaping the openings will be hereinafter explained.

90 At the opposite ends of the side frame 1 there are provided journal boxes 10, said journal boxes being formed as integral portions of the side frame. In order to reduce the moment arm of the transverse and longitudi-

55

nal forces which are applied approximately at the top 11 of each journal box, I so form the top member that adjacent each inner wall 12 the said journal boxes are intersected by a tension member 3; that is, the intersection of the plane of the tension member with each journal box is below the plane of the roof 11. I am enabled to so form the journal boxes by sloping the adjacent portion of the roof 10 downwardly from the inner face of the adjacent wedge guide and brass lug 13. This construction, which is clearly illustrated in Figure 4, does not interfere with the application of the wedge and at the same time enables 15 the top of the journal box to be placed relatively close to the point of intersection of the neutral axes 14 and 15, respectively, of the tension and compression members, the said neutral axes being illustrated in the cross-sectional portion of Figure 1 by correspondingly numbered dot and dash lines. This chamfering or sloping of the roof of each journal box is preferably continued between the side walls 20 of the frame, as indicated in Figure 1, and 25 from the back or inner side wall to the dust guard well, as illustrated in Figure 2. It will also be observed that the point of intersection of the neutral axes is disposed at a relatively low level on the vertical axis of the 30 said journal box, which materially reduces the stresses transmitted to the side frame by the weight of the car and the movements of the car incident to service. This arrangement is effected by sloping the roofs of the boxes, 35 thereby permitting the disposition of the tension and compression members with their neutral axes disposed at relatively low levels.

Each of the side walls 12 of the journal boxes 10 is connected to the adjacent tension 40 member by a pair of webs 16, the said webs being spaced inwardly from the outer faces 6 of the said side frame and having their lower faces in alignment with the plane of the journal bearing (not shown), or the axis 45 thereof, whereby the dynamic forces transmitted to the side walls 12 of each journal box, due to brake application, etc., are transmitted to a large area of the tension member and thus dissipated or neutralized 50 without causing the hinging action of the journal box about the plane of intersection of the tension member with the side wall.

In a truss where the points of connection 55 between the members are rigid, as in a cast truck, there is always deformation caused in the truss members by the application of the load thereto. This deformation is due to the elastic yield of the truss members. The elastic yield of the truss member causes 60 secondary stresses to be set up in the truss members, which secondary stresses increase in both directions from the intersection of the normal line of each truss member and the deformed truss member; that is, each truss member deforms in the shape of a curve which

may, for convenience and without the use of technical and mathematical terms, be called an **S** curve, and at the points where the **S** curve intersects with the normal line of the truss member, called the points of contra-flexure, it will be obvious that the secondary stresses are zero or reduced to a minimum since at this point each truss member is in its normal position despite the elastic deformation of other portions of the truss. I have found that a large amount of breakage of side frames is caused by the failure of inventors to consider this elastic deformation of the truss members and hence their failure to compensate for the secondary stresses. I have overcome this defect in the side frame which I have illustrated, by the formation of the marginal edges of the openings 7, the said marginal edges being so formed that at the points of contra-flexure, which may be 70 designated by the letters X and Y, the depth of the flanges of the compression and tension members is reduced to a minimum and that these flanges increase in depth in both directions from the points X and Y so as to 75 compensate for the secondary stresses and that at points adjacent the ends of the side frame where the secondary stresses are greatest and where the end portions of the tension and compression members are 80 further subjected to twisting, wrenching and other strains, the flanges extending from each of said members are united so as to form a 85 closed box section giving the greatest possible strength for the least weight of material. 90

It will be observed that where the walls 4 of the window opening join the downwardly extending flanges of the compression member 2 I have extended the fillets 17 so as to avoid abrupt changes in the thickness of 95 metal and have in this manner materially strengthened the center portion of the compression member against its compression loads. 105

Adjacent the points of connection of the tension member 3 with the journal boxes, the said tension member is provided with laterally projecting webs or flanges 18 which are integrally connected with and merge into the top wall of the said journal boxes. This construction materially reinforces the journal boxes against the forces caused by the change 110 in angularity of the car axle. 115

It might be here pointed out, as is clearly evident from an inspection of Figure 1, that a 120 plane passed through the neutral axis of the tension member, and parallel to the web thereof when projected outwardly, actually intersects the adjacent side wall of the journal box. This construction is possible only 125 by the formation and mode of connection between the tension member and journal boxes, as has heretofore been described. The benefits which are derived from this construction have been noted at a previous point in the 130

specification. Attention here might be called to the fact that by so locating the journal boxes with reference to the neutral axis of the tension member, the moment arm by which the forces impressed upon the journal boxes react upon the truss members of the side frame is reduced to a minimum.

From a consideration of the foregoing disclosure it will be seen that I have devised a frame in which the compression member is 10 inverted U-shape for its entire length, while the tension member changes from U-shape at its end or inclined portions to inverted U-shape at its central portion beneath the bolster opening, the web shifting from a lower 15 to an upper position.

Although I have described a preferred embodiment of my invention, it will be understood that modifications may be made within 20 the spirit and scope of the appended claims.

Having now described my invention, what I claim is:

1. In a truck side frame, the combination of tension and compression members, of journal boxes integrally connected therewith and provided with brass lugs, said journal boxes being disposed with the vertical axes thereof on the intersection of the neutral axes of said tension and compression members, the lower 25 wall of the tension member connecting with each journal box top wall substantially in line with the inner brass lug thereof.

2. In a truck side frame, the combination with compression and tension members, of journal boxes integrally connected thereto, side walls integral with said tension and compression members, said side walls having 30 openings therein, said openings being so disposed that the flanges defined by their marginal edges increase in width from points corresponding to the points of contra-flexure of the said tension and compression members.

3. In a truck side frame, the combination with connected tension and compression members and an interposed strut, of journal boxes integrally connected to the end portions of said tension and compression members directly below the points of intersection of the neutral axes thereof, the planes of intersection of the lower portion of said tension member with said journal boxes being below 45 the plane of the roof of said journal boxes.

4. In a truck side frame, the combination with tension and compression members and an interposed strut, of journal boxes integrally connected to the end portions of said compression and tension members, the inner side walls of said journal boxes being connected to the adjacent portions of the tension member by a plurality of webs, said webs having their lower faces arranged substantially parallel with the line of thrust for dynamic forces transmitted to the adjacent side wall of said journal boxes by the journal bearing within the same.

5. In a truck side frame, the combination of tension and compression members, of journal boxes integrally connected thereto, said journal boxes being below the junctions between said members and disposed with the vertical axes thereof on the intersection of the neutral axes of said tension and compression members, the neutral axis of said tension member being adapted when projected outwardly to intersect a wall of said journal box. 70

6. In a truck side frame, the combination with connected tension and compression members and an interposed strut, of journal boxes integrally connected to the end portions of said tension and compression members below the connections therebetween, the planes of intersection of said tension member with said journal boxes being below the plane of the roof of said boxes, and means formed on said tension member and extending laterally therefrom and integrally connected to said journal boxes for reinforcing the connection therebetween. 75

7. In a truck side frame, the combination with a cambered compression member, a tension member, a pair of spaced upright members integrally connected to said tension and compression members, said upright members constituting an interposed strut, said compression member at points intermediate said upright members being substantially U-shaped in cross-section, and fillet means connecting the arms of said U at the junctions of the upright members therewith and serving to effect a gradual change in cross-sectional area, by decreasing in depth from said upright members to merge with the arms of said U substantially midway between said upright members. 80

8. A truck side frame comprising tension and compression members generally U-shape in cross-section and journal boxes integrally connected to said frame at the ends thereof, said journal boxes being disposed below the intersection of the neutral axes of the tension and compression members, positioned with the vertical axis of each substantially on the corresponding point of intersection of the neutral axes, and connected to the web of the compression member by transverse webs lying on said vertical axes.

9. A truck side frame comprising compression and tension members formed with webs and flanges on opposite sides of said webs, said flanges defining openings therebetween and formed of increasing width from points of contra-flexure of the compression and tension members.

10. A truck side frame comprising integrally connected tension and compression members formed with webs and flanges on the sides thereof, a strut portion spacing intermediate portions thereof, journal boxes integrally connected to the frame below the end portions of said tension and compression 125

- members with their vertical center lines lying approximately on the points of intersection of continuations of the normal neutral axes of said members, the lower portion of said tension member intersecting the journal boxes below the plane of the upper surface thereof.
11. A truck side frame comprising tension and compression members spaced at their intermediate portions by a strut portion, journal boxes integrally connected to said compression and tension members, the inner side walls of said journal boxes being connected to the adjacent portions of the tension member by webs, the lower edges of which are positioned substantially horizontal.
12. A truck side frame comprising tension and compression members, journal boxes integrally connected thereto, said journal boxes being arranged below the ends of said members and positioned with the vertical axis of each approximately on the corresponding point of intersection between the neutral axes of the tension and compression members, the lower portion of said tension member, when continued outwardly, intersecting the adjacent wall of the corresponding journal box.
13. A truck side frame comprising a compression member inverted U shape in cross section, a tension member U shape in cross section, the flanges of said U sections merging adjacent the ends of the frame, journal boxes integrally connected adjacent the ends of said frame and formed with brass lugs, the lower web of the tension member extending to said journal boxes and connected with the top walls thereof substantially in line with the inner brass lugs.
14. A truck side frame comprising a compression member formed with an upper web and depending flanges from opposite edges of said web, a tension member formed with a lower web and upstanding flanges from opposite edges thereof, journal boxes integrally connected with said frame adjacent the ends thereof and provided with brass lugs, the flanges of the compression and tension members merging adjacent the journal boxes and extending over the tops thereof, the web of said tension member meeting the roofs of said journal boxes substantially at the junctions with the inner brass lugs.
15. A truck side frame comprising a tension member formed with a web and flanges on opposite edges of said web, said flanges being formed of increasing width from points of contra-flexure of said tension member.
16. A truck side frame comprising a compression member formed with a web and flanges on opposite edges of said web, said flanges being formed of increasing width from points of contra-flexure of said member.
17. A truck side frame comprising compression and tension members spaced at intermediate portions by bolster guide columns

and integrally united at their ends, said tension member being formed with a web and flanges on opposite sides of said web, said web extending substantially straight from the bolster guide columns outwardly to the ends thereof, the free edges of said flanges, outwardly of said bolster guide columns, being curved for their entire length.

18. A truck side frame comprising compression and tension members integrally uniting at their ends with journal boxes and each other and spaced at intermediate portions by bolster guide columns, said bolster guide columns being of minimum cross sectional area at intermediate portions thereof and increased in cross sectional area toward the ends thereof, the lower portions of said bolster guide columns being flared outwardly from the intermediate portions thereof to unite with the end portions of the tension member in a direction more nearly perpendicular thereto, the ends of said tension member likewise flaring to unite with the sides of the boxes.

19. A side frame comprising a compression member and a tension member uniting at their ends, integral journal boxes connected thereto, a web of said tension member joining with the inner wall of each journal box below the roof thereof, said roof being sloped to correspond with the slope of said tension member and form a continuation of said web.

20. A side frame comprising a compression member and a tension member joining at the ends thereof, said tension member being generally U-shaped in cross section, integral journal boxes at the ends of said frame, the web of the tension member extending to meet each journal box at the inner side wall thereof below the roof, said roof, at this point being sloped to form a continuation of the web of said member.

21. A side frame comprising a compression member, a tension member, said members joining at the ends thereof, integral journal boxes connected to said members at the ends of the frame, said tension member being formed with a web intersecting the inner side wall of each journal box below the roof thereof, that portion of the roof of the journal box, between said tension member and the rear or inner portion of said roof, being sloped to correspond with the slope of said tension member to form, in effect, a lateral extension thereof.

22. A side frame adapted for use in a railway car truck comprising a compression member formed with an upper web and depending flanges on opposite edges thereof, a tension member formed with a lower web and upstanding flanges on opposite edges thereof, the intermediate portion of said tension member being substantially horizontal with end portions sloping outwardly and

upwardly to join with the ends of the compression member, journal boxes integrally connected with said frame adjacent the intersection between said compression and tension members, said boxes being formed with brass lugs comprising walls spaced inwardly from the side walls of the boxes and joining with said tension member, the web of said tension member extending outwardly past the inner walls of said journal boxes where it is extended substantially horizontally as the roofs of said boxes, the location of the change in direction from inclined to substantially horizontal corresponding to the union with the inner wall of the inner brass lug.

23. In a side frame, in combination, a tension member, a compression member, said members being connected together at an extremity of said side frame, a journal box connected to said side frame at said extremity of said side frame, said journal box having its inner upper edge bevelled, said tension and compression members being shaped to have their neutral axes at relatively low levels, said tension member being a channel section, the web of said tension member being in substantial alignment with said bevelled edge.

24. A side frame comprising a bolster receiving portion, a compression member connected to the upper part of said bolster receiving portion, a tension member connected to the lower part of said bolster receiving portion, said tension and compression members being disposed in angular relationship with each other and being connected together at their outer ends, a journal box joined to said tension and compression members adjacent to the point of junction of said members, said tension and compression members comprising channel sections having their neutral axes disposed at a relatively low level, which neutral axes intersect substantially at the vertical central plane of said journal box, the inner upper edge of said journal box being bevelled, the web of the channel section of said tension member being disposed in substantial alignment with said bevelled edge.

25. A side frame including a tension member and a compression member joined together at an extremity of said side frame, a journal box at said extremity, said tension and compression members comprising channel sections having their extremities provided with strengthening flanges, the neutral axes of said tension and compression members being disposed at relatively low levels in said tension and compression members, said neutral axes being disposed in positions to intersect substantially in the vertical central plane of said journal box, said journal box having its upper inner edge portion bevelled, said tension member having the web portion of its channel section disposed in

substantial alignment with said bevelled portion of said journal box.

26. In a truck side frame, a compression member with an upper web and depending flanges, a tension member with a lower web and upstanding flanges, journal boxes integrally connected therewith and provided with brass lugs, said boxes being disposed with their vertical axes on the intersection of the neutral axes of said tension and compression members, the web of said tension member connecting with each journal box top wall at approximately the point of intersection with the inner brass lug thereof.

27. In a truck side frame, in combination with connected tension and compression members and an interposed strut, journal boxes integrally connected to the end portions of said tension and compression members, said tension member extending over and joining the top of the box, each box lying with its vertical axis on the point of intersection of the neutral axes of the tension and compression members at the corresponding end of the frame, the plane of intersection of the lower portion of said tension member with each journal box being below the plane of the roof of said box.

28. A truck side frame comprising a compression member generally inverted U-shape in cross-section, a tension member generally U-shaped in cross-section, said compression and tension members being spaced at intermediate portions thereof by bolster guide columns and extending straight outward to the ends of the frame and united to each other and to integrally formed journal boxes adjacent each end of said frame, the connection between each journal box and the frame being strengthened by a plurality of upright laterally spaced webs extending longitudinally from the web of the tension member to the adjacent side wall of the journal box.

29. A side frame comprising a compression member and a tension member uniting at their ends, journal boxes integrally connected at each end of said frame, said tension member being formed with a web and side flanges, said web joining with the inner wall of each journal box below the normal level of the roof thereof and continued onward to form a sloping roof portion of each box and unite with the main portion of each box roof approximately in the vertical plane of the inner face of the adjacent brass lug.

30. A truck side frame comprising tension and compression members joined at their ends, journal boxes integrally connected to the frame adjacent the ends of the members, bolster guide columns spacing intermediate portions of the compression and tension members and defining a bolster opening therebetween, said tension member being formed generally U-shape in cross section with a web extending below the bolster opening and con-

tinued as the lower web of said member straight from either side thereof diagonally upward from the lower corner of the bolster opening to the adjacent journal box slightly below the upper inner corner thereof, where 5 it is attached to the box side wall.

31. A truck side frame comprising tension and compression members, said tension member being formed substantially box shape 10 along the intermediate portion thereof and U shape along the diagonal end portions thereof with a lower web and upstanding flanges on either side of said web, said compression member being formed generally 15 channel shape in cross section with an upper web and depending flanges on either side of said web, the flanges of said members merging at their ends, journal boxes integrally connected to the frame adjacent the ends of 20 said members, bolster guide columns spacing intermediate portions of the compression and tension members and defining a bolster opening therebetween, the upper web of said tension member below the bolster opening being 25 continued straight from either side thereof diagonally upward as the lower web of the diagonal end portions of said tension member to the adjacent journal box to join therewith slightly below the upper inner 30 corner thereof.

32. A truck side frame comprising tension and compression members, journal boxes integrally connected to said frame adjacent the ends of said members, bolster guide 35 columns spacing intermediate portions of the compression and tension members and defining a bolster opening therebetween, said columns having vertical web portions merging with the upper portions of the tension members 40 beneath said bolster opening, said tension member being formed with an upper web extending below the bolster opening between the vertical webs of the bolster guide columns and from there continued straight to either 45 side thereof diagonally upward as the lower web of the tension member to the adjacent journal box where it connects therewith at a point slightly below the upper inner corner thereof.

50. 33. In a truck side frame, the combination with tension and compression members and an interposed strut, of journal boxes integrally connected to the ends of said frame, the lower portion of said tension member extending straight out and intersecting the journal boxes at a point slightly below but near the lower surface of the roof of each box, and reinforcing gusset means extending between the lower portion of said tension member and 55 the adjacent side walls of the journal boxes.

34. A truck side frame comprising compression and tension members formed with webs and flanges on opposite sides of said webs, journal boxes integrally connected to 60 the frame adjacent the ends of said members,

bolster guide columns spacing intermediate portions of the compression and tension members, leaving a window opening therebetween, said tension member, beneath the window opening, having an upper web which is continued straight from either side thereof diagonally upward as the lower web of diagonal end portions thereof to the adjacent journal box to join therewith slightly below the upper inner corner thereof.

In testimony whereof I affix my signature.
THOMAS H. SYMINGTON.
